UNITED STATES PATENT OFFICE.

WALTER LESLIE STADIG, OF ST. FRANCIS, MAINE.

SNOW-PLOW AND SNOW-LOADER.

1,314,762.

Specification of Letters Patent.

Patented Sept. 2, 1919.

Application filed October 11, 1918. Serial No. 257,757.

To all whom it may concern:

Be it known that I, WALTER LESLIE STADIG, a citizen of the United States of America, and resident of the town of St. Francis, in the State of Maine, in the United States of America, have invented certain new and useful Improvements in Snow-Plows and Snow-Loaders, of which the following is the specification.

10 The invention relates to improvements in snow plows and snow loaders, as described in the present specification and illustrated in the accompanying drawings, that form part of the same.

15 The invention consists essentially in the novel arrangement and construction of parts, whereby the roadway is cleared and the snow directed away from the machine in the delivery thereof.

20 The objects of the invention are to provide in a snow clearing machine certain advantages, which constitute subject matter divided from copending application Serial No. 250,075 and improvements on the machines described in the specifications attached to Letters-Patent of the United States Nos. 1,084,498 and 1,093,498 on January 13th, 1914, and April 14th, 1914, said improvements much facilitating the operation of the machine and insuring a wider application of the same; and generally to furnish a machine to the public, that will prove efficient and economical for clearing road-ways of accumulations of snow in the winter time.

In the drawings, Figure 1 is a side elevation of the machine.

Fig. 2 is a front elevation of the machine showing the plowshare and an extension chute for loading purposes and omitting the running gear.

Fig. 3 is a side view of a portion of the machine showing the particular parts illustrated in Fig. 2.

Fig. 4 is a plan view showing the same parts, pertaining to this invention, and illustrated particularly in Figs. 2 and 3.

Like numerals of reference indicate corresponding parts in each figure.

Referring to the drawings, the main frame 1 is carried on the sleds 2 and 3, the former sled 2 being the front or guiding sled and the latter sled 3 the rear sled, said sleds being equipped with means for turning, so as

to direct them to the roadside in particular places.

The front sled 2 is here shown as arranged for draft power such as horses, though any power may be used for propelling purposes and said sleds may be in the form of wheel trucks and driven accordingly or the machine may be hauled by a motor driven vehicle.

The driving gear shaft 4 is journaled in suitable bearings supported by the frame 1 and is operatively connected to the motor 5.

The beams 6 swing on the shaft 4 and slope downwardly. The bars 7 are rigidly secured to the upper sides of the beams 6 and the bars 8 are rigidly secured to the lower sides of said beams and extend beyond said bars 7, the latter being bent downwardly and secured to the bars 8 by means of the pivot bolts 9.

The bars 10 extend upwardly from the pivot bolts 9 and are pivotally secured to cranks 11, fixedly mounted on the shaft 12, said shaft 12 being rotated by the segmental gear 13. The segmental gear 13 is operated by the worm 14 at the end of the shaft 15 on which is mounted the hand wheel 16.

It will now be seen that by turning the hand wheel, the worm, coacting with said segmental gear, will operate said gear and consequently the cranks, thereby raising or lowering the said beams through said suspension bars 10.

The bearings 17 are supported at the lower ends of the beams 6 and in these bearings the cutter shaft 18 is journaled.

The cutters 19 are fixedly mounted on the shaft 18 at each side of the machine and are formed of the vanes 20 of considerable length transversely of the machine and in cross section of spider shape, said vanes having the knives 21 in contact with the snow.

The cutters 19 are rotated with the shaft 18 and the latter is driven by the chain 22 and sprockets 23 and 24, said sprockets being mounted on the shafts 18 and 4.

This driving mechanism turns the said cutters several hundreds of revolutions per minute, which has the effect of driving great quantities of snow upwardly and for that reason the inclosed chutes 25 are provided, said chutes communicating with the flaring and substantially semi-circular hoods 26 reinforced by the heavy plates 27, that extend

beyond the hoods at each end and form baffles to protect the machinery from the flying snow and also rigid supports for other parts of the mechanism.

- 5 The extension hood 28 is firmly secured by hinges 29 to the plates 27, on either side or one on each side if found convenient, and projects in an oblique direction outwardly in alinement with the main hood 26, and is 10 separable therefrom, so that it may be transferred as stated aforesaid from one side to the other to coincide with the work of the scraper plow as described hereinafter.

The extension hood 28 terminates at its 15 upper end in a canopy top 30, and has the outer hinged deflecting plate 31, this plate being hinged to said canopy top and extending thereacross and at each end terminating in the inwardly turned flanges 32.

- 20 The extension hood 28 forms the middle section of the delivery hood, the top section 30 being hinged to said middle section and extending outwardly therefrom as a curved deflecting plate for directing the snow downwardly. The transverse deflecting plate 31 is pivotally suspended from the outer end of the top 30 and is inwardly turned at each end, forming the flanges 32, thereby providing a deflecting plate for continuing the fall 30 of the snow from the deflecting top into a convenient conveyance alongside the machine.

The hood section 28 is operated by the cable 33 and chain 35, the links of said chain 35 locking in the ring 36 slotted at 37 in the bracket 34.

- It is more satisfactory with the extension hood to use a plow 43 formed and mounted like a scraper. This scraper plow 43 is 40 rigid with the frame 44. The frame 44 is formed with the flanges 45, which are secured to the bars 8 by the bolts 46, therefore the frame 44 is suspended by the bars 10 and adjusted by the reach bar 47, having 45 the turnbuckle 48 and secured to an eye 49 from the machine body and to the eye bolt 50 secured in the frame 44. The brace 51 is secured across the V-sections of the frame 44. The scraper plow 43 is rigidly secured 50 to one of the V-sections of the frame and extends therefrom to the opposite side of the machine, the extreme end being connected to the machine body by the chain 52. The strut 53 extends from a bolt 46 to the back of 55 the scraper plow 43 and is rigidly secured thereto.

The plow 43 is finished off at its lower end in the steel knife 54 and extends across from the inner end of a cutter 19 in an angular direction to the far side of the machine 60 in front of the other cutter, completely blocking the latter, so that all the snow is directed to the uncovered cutter and this drives it into the chute above, whereby 65 means of the centrifugal force and the cur-

rent of air created by the rapid revolution of the cutter, it is driven into the extension hood 28 and against the deflecting plate and so down into the accompanying vehicle to be transported to the dumping ground.

70 The rotary cutters on each side are preferably inclosed from the outer sides by the casings 55, into which the snow is guided and elevated by the cutters.

In the operation of the invention, the machine is drawn along the road to be cleared and the cutters set in motion. The scraper plow cuts the packed snow and directs all the snow in its path into the path of a cutter and by means of the elevating vanes the 80 snow is lifted into the chutes, from which it reaches the hood and is flung off the edges of said hood against the canopy and deflecting plate and deposited.

85 Various changes may be made in the construction of this machine and in its mode of operation without departing from the spirit of the invention so long as they are within the scope of the claims.

90 What I claim is:—

1. In a machine of the class described, a frame, means for gathering and elevating the snow, a chute and delivery hood, forming a discharge passage in sectional pieces the middle section being a removable extension hood joining a top forming a downwardly deflecting surface.

95 2. In a machine of the class described, a frame, a rotary cutting and elevating member suitably driven, a delivery hood, and a 100 scraper plow extending in an oblique direction from the inner edge of the cutter to the extreme opposite side of the machine and directing the snow into said cutter.

3. In a machine of the class described, a frame, a rotary cutting and elevating member, and a chute and delivery hood, forming a discharge passage in sectional pieces, the middle and top sections being removable, the latter extending outwardly in suitable 110 shape to direct the snow downwardly, said middle section being hinged to the fixed parts and said top section to said middle section.

4. In a machine of the class described, a rotary cutting and elevating member, a chute 115 and delivery hood, a reinforcing plate wall extending over and beyond said hood, an extension hood hinged to said plate wall and having a deflecting upper end, a deflecting plate hinged at the extreme end of said 120 deflecting upper end, and cables for operating said deflecting top and plate.

5. In a machine of the class described, a frame, means for gathering and elevating the snow, a chute and delivery hood, an extension hood having a deflecting top and 125 hinged to said delivery hood, a deflecting plate hinged at the outer edge of said deflecting top, a cable attached to said deflecting top, a cable attached to said deflecting 130

plate, said cables being connected to locking chains and said hoods projecting upwardly and outwardly in an inclined direction from the machine and adapted to deposit the snow in accompanying vehicle.

6. In a machine of the class described, a frame, elevating means, a delivery hood, a chute leading upwardly from said elevating means and having a side wall rigidly secured to the lower frame of said delivery hood and forming a deflecting plate for the plow discharge, and a plow for directing snow to said elevating means.

7. In a machine of the class described, a

frame, running gear, rotary cutters forming 15 elevating means, side plates forming barriers in directing snow to said cutters, a scraper plow, means for adjusting the cutting angle of said plow, an inclined casing above said barriers, a plurality of extension 20 parts connected by hinges to one another and to said inclined casing the upper of said extension parts having a canopy top, and a deflecting plate hinged at the outer end of said canopy top.

Signed at Montreal, Canada, this 26th day of September, 1918.

WALTER LESLIE STADIG.
